UNITED STATES PATENT OFFICE.

ANDREW E. MARKWELL, OF FORT WORTH, TEXAS, ASSIGNOR OF ONE-HALF TO C. W. STANTON, OF FORT WORTH, TEXAS.

MATRIX-MOLDING DEVICE.

1,072,137.

Specification of Letters Patent.

Patented Sept. 2, 1913.

Application filed April 17, 1913. Serial No. 761,714.

To all whom it may concern:

Be it known that I, ANDREW E. MARKWELL, a citizen of the United States, residing at Fort Worth, in the county of Tarrant 5 and State of Texas, have invented certain new and useful Improvements in Matrix-Molding Devices, of which the following is a specification.

My invention relates to improvements in 10 matrices and more particularly to devices which are facsimiles in appearance to matrices and which are adapted to mold rule holding members on the top lines of line-cast slugs, and the object is to provide simple devices which are carried by the matrices or molding devices for forming rule retaining members which have angular grooves therein for holding printing rules in place on type forms. 15

Another object is to provide such molding devices which have the general form of matrices so that the molding devices can be handled by line-casting machines in the same manner as matrices are handled. 20

Other objects and advantages will be fully explained in the following description, and the invention will be more particularly pointed out in the claims. 25

Reference is had to the accompanying drawings which form a part of this application.

Figure 1 is a side view of an enlarged view of a form which makes raised portions on the printing edges of slugs. Fig. 2 is a 35 view of the opposite side of the same form. Fig. 3 is a view of the same in the same position as in Fig. 2, but with the cover removed to expose the interior cavity and the movable part located in the cavity. Fig. 4 is an enlarged cross-section, taken on the line A—A of Fig. 2. Fig. 5 is a similar view to Fig. 4 with the forming device at the point of separation from the slug. 40

Similar characters of reference are used 45 to indicate the same parts throughout the several views.

The forms consist of a bar 1 and cover 3 and the two parts together make facsimiles of the matrices used on linotype and inter- 50 type or line-casting machines, having the

same dimensions and other features as the matrices in use and operable or capable of being handled by line-casting machines now in use for handling such devices. These forms are set up in a line with ordinary 55 matrices in order to cast a slug having on its face the usual printing characters and also the projections with grooves therein for holding the printing rules. A cavity 2 is formed within the bar 1 and in order to 60 make the cavity 2 accessible, a part of the bar 1 is formed into a cover 3 which can be fastened on the bar after the bar is provided with the operating devices within the cavity 2. 65

The object of this invention is to form elevations 4 on the printing edge of line-cast slugs 5 with under-cut or under-beveled edges 6, thus forming grooves through the elevations 4 to receive printing rules and 70 hold the same against displacement. The portions of the elevations on each side of the groove form rule holders or rule holding members and these members should be of less height from the top line of the slug 75 than the height of type or printing edge of the rule. These grooves will be uniform so that when a type form is made up a rule can be horizontally inserted from one side of the type form. For accomplishing this 80 object spring groove formers 7, having arms 8, are mounted within the matrix bars 1. Normally the spring groove former 7 is held within the bar 1 by a spring 9 which has one end rigidly secured to the bar 1 85 and the other end resting loosely on the former 7 between the arms 8. The arms 8 have angular grooves 10 at the upper edges and the bar 1 and the cover 3 are cut away as deep as the bottom edges of the grooves 90 10. The angular grooves in the arms 8 and the cavities formed by the cut away portions of the bar 1 and the cover 3 form the spaces for molding the rule-holders or rule-holding members 4. A portion of the 95 bar 1 is left between the ends 12 of the arms 8 to form a bridge 11 for spacing the ends 12 apart while the members 4 are being molded. The ends 12 and the bridge 11 serve to make the groove between the mem- 100

bers 4 the proper width. The molten material or metal for casting the members 4 and slug 5 is forced in the molds by the action of the line casting machine in casting a slug 5 while the arms 8 occupy the positions shown in Figs. 2, 3, and 4. After the members 4 and the groove therein are formed on the slug, the slug 5 is made to recede or is separated from the casting position, and while 10 receding the members 4 will draw the spring groove former 7 partly out of the bar 1 or molding device 1, as shown in Fig. 5, until the ends 12 of the groove former 7 are far enough from the bridge 11 to allow 15 the arms 8 to spring inwardly so that the ends 12 will escape from the angular groove between the members 4. As soon as the ends 12 are released from the members 4, the spring 9 will draw the forming device 20 7 back within the molding device 1. The groove former 7 will thus be drawn back to its normal position within the molding device. The member 8 may be called a groove former or a rule-holder former. In 25 each action the members 4 are formed by the molding devices and the groove former 8 will be partly withdrawn from the molding device 1 by the members 4 of the slug 5 and will disappear within the molding device as soon as released from the members 30 4 so that the molding device 1 can be handled by the line-casting machine just as an ordinary matrix is handled.

It will be understood that the contour of 35 the arms 8 with the grooves 10 therein and the ends 12 can be changed and other changes in the construction can be made without departing from my invention.

What I claim, is,—

40 1. A matrix molding-device provided with a cavity therein, a rule-holder former mounted therein and having arms projecting from said cavity flush with the surface of the molding device and being movable 45 for releasing the slugs and having angular grooves in the exterior surfaces thereof.

50 2. A matrix molding-device provided with a cavity therein, a rule-holder former mounted therein provided with arms projecting therefrom and a bridge spacing said arms apart, said arms having grooves in their exterior faces and said former being movable between said bridge and the bottom of said cavity.

55 3. A matrix molding-device provided with a cavity therein, a rule-holder former mounted therein provided with arms projecting therefrom and a bridge spacing said arms apart, said arms having angular 60 grooves in their exterior exposed surfaces.

4. A matrix molding-device having a cavity therein, a spring actuated forming device mounted in said cavity and provided with arms projecting therefrom for mak-

ink rule holding members on printing slugs, 65 said arms having grooves for forming bevel faces on the inside of the rule holding members.

5. A matrix molding-device provided with a cavity therein, a rule-holder former 70 mounted therein and provided with spring arms projecting therefrom, said arms having grooves in their exterior faces for forming bevel faces on the inside of the rule-holding members. 75

6. In a slug line-casting mechanism, a matrix having forming devices mounted therein for forming bevel faced rule holding members on the type line of slugs, said forming devices being movable for the purpose of releasing said members when the slugs are being withdrawn. 80

7. In a slug-casting mechanism, a matrix having forming devices mounted therein for forming bevel faced rule-holding members on the type line of the slugs, said forming devices being adapted to be partly withdrawn from the matrix, and means in said matrix for automatically retracting said forming devices within the matrix. 85 90

8. A matrix molding-device having a cavity therein, a groove former mounted therein and provided with spring arms projecting therefrom, said arms having grooves in their exterior faces in the projecting portions and said molding device having cut-outs adjacent to the projecting ends of said arms. 95

9. A matrix molding-device having a cavity therein, a forming device mounted in 100 said cavity and provided with spring arms projecting therefrom and adapted to be partly withdrawn therefrom and a spring mounted in said cavity for drawing said forming device back into normal position. 105

10. A matrix molding device having a cavity therein, a forming device mounted therein and provided with spring arms projecting therefrom, a bridge spacing the projecting portions of said arms apart, and a 110 retractile spring in said cavity engaging said forming device.

11. A matrix molding-device having a cavity therein, a forming device mounted therein for forming rule-holding members 115 on the type line of printing slugs and provided with spring arms projecting therefrom, said arms having angular grooves in their outer faces for receiving the forming elements, said forming device being movable by the rule-holding members after they are formed, and a retractile spring for drawing the forming device back into said cavity. 120

12. A matrix molding-device having a 125 cavity therein, a rule-holder former mounted therein and provided with spring arms projecting therefrom, said arms having an-

gular grooves in their outer faces for receiving the forming element, a bridge rigid with said matrix molding-device, said bridge and the ends of said arms serving to form a 5 groove through the rule holder with beveled walls facing each other, and a retractile spring in said cavity engaging said former.

In testimony whereof, I set my hand in the presence of two witnesses, this 10th day of April, 1913.

ANDREW E. MARKWELL.
